UNITED STATES PATENT OFFICE

126,223

DESIGN FOR A THERAPY TANK

Floyd W. Ille, New York, N. Y.

Application December 12, 1940, Serial No. 97,270

Term of patent 14 years

To all whom it may concern:

Be it known that I, Floyd W. Ille, a citizen of the United States of America, residing at New York, in the county of New York and State of New York, have invented a new, original, and ornamental Design for a Therapy Tank, of which the following is a specification, reference being had to the accompanying drawing, forming part thereof.

I claim:

The ornamental design for a therapy tank, as shown.

FLOYD W. ILLE.
